UNITED STATES PATENT OFFICE.

HUGH MOORE, OF MAUCH CHUNK, PENNSYLVANIA, ASSIGNOR OF TWO-THIRDS TO ALVIN SCOTT AND SAMUEL CARPENTER.

BROOM-BRIDLE.

SPECIFICATION forming part of Letters Patent No. 394,658, dated December 18, 1888.

Application filed November 8, 1887. Serial No. 254,644. (Model.)

To all whom it may concern:

Be it known that I, HUGH MOORE, a citizen of the United States, residing at Mauch Chunk, in the county of Carbon and State of Pennsylvania, have invented new and useful Improvements in Broom-Bridles, of which the following is a specification.

My invention relates to improvements in broom-bridles; and it has for its objects the provision of a device to hold brooms in shape, which will not merely embrace them at one or two points, but will inclose the same and form a net-work of supporting rods or wires.

A further object of the invention is the provision of improved means of securing the said bridle in place.

With these objects in view, the invention consists in forming a wire bridle in two sections, the adjacent wires or rods of which are drawn together by small rings sliding thereon. The said sections are hinged together at the upper ends, and are free at the lower ends to allow the bridle to be easily applied to the broom. After the bridle has been adjusted the said rings are slipped down the side wires of the sections, and the lower ends of the sections are thus secured together.

The invention consists, further, in certain novel details of construction and arrangement, more fully set forth hereinafter, and described in connection with the drawings, wherein—

Figure 1 is a side view of a broom provided with one of my improved bridles. Fig. 2 is a perspective view of the bridle detached. Fig. 3 is a side view of the bridle, showing it extended, as when about to be applied to a broom.

Referring to the accompanying drawings, in which similar letters denote corresponding parts in all the figures, A A' designate the two sections of the bridle. The section A is provided at the inner side with the side rods or wires, B B, which are provided at their upper ends with the eyes b b. The rods B B and the eyes b b are formed of a single piece of wire, a, and after forming the said eyes the portions of the wire are extended outward a short distance to form the arms D D, which have the spring-coils C C at intermediate points of their length.

On the outer side of the coils C the ends of the arms D D are drawn together and twisted, as seen at x. The section A' is exactly similar in every respect to the section A, and it has the side wires or rods, B' B', provided at their upper ends with the eyes b' b', the rods or arms D' D' extending outward from the said eyes b' and the coils C' C' at intermediate points of the arms D'. The outer ends of the arms D' D' are drawn together beyond the coils C' and twisted, as seen at x'. The adjacent eyes b b and b' b' of the two sections are looped or engaged together, thus hinging the two sections firmly together at the upper ends. The said arms or rods D D and D' D' converge, respectively, toward their outer ends. It will now be seen that the converging arms D, together with the similar arms, D', form the ring E, which is adapted to embrace the handle of the broom and thus maintain the bridle in position.

The portions of the wires a and a' are separated beyond the twists x and x' and extended downward to form the depending rods F F and F' F', which are provided at their lower ends with the eyes G G and G' G'.

H H' designate horizontal rigid loops, which are formed by the centers of the wires a and a', and the said loops are arranged, respectively, between the eyes G G and G' G'.

It will be seen that the depending rods F F and the loop H form together a depending arm, which is drawn by the links K K' against the side or edge of the broom, and there is a similar spring-actuated arm on the other section and formed by the arms F' F' and the loop H'.

The lower ends of the rods B B' are provided with the eyes I I', respectively, and short links K K' are engaged at the ends in the eyes G G' and I I' to tie the lower ends of the rods F F' to the lower ends of the rods B B'.

L L' designate loops, which are provided with eyes l l' at the inner ends to engage in the eyes I I', thus pivoting or hinging the said loops to the frame of the bridle.

It will now be clearly seen that the sections A A' are entirely independent of each other, with the exception of being hinged together at the upper ends by the engagement of the

eyes b b and b' b' . Thus the lower ends of the sections are free to swing apart and allow the bridle to be readily placed upon the broom.

- 5 M M designate rings, which embrace the adjacent rods B B', and they are adapted to slide on the said rods to draw the lower free ends thereof together, and thus secure the lower ends of the sections together. When 10 the bridle is about to be placed on a broom, the rings M are slipped up to the upper ends of the rods B B', and after the bridle is properly adjusted the rings are drawn down to draw the lower ends of the sections together, 15 and thus compress the broom-corn into the desired shape. This compression is caused, as will be readily understood, by the rigid and pivoted loops H and L pressing the said broom in opposition to the loops H' and L'. 20 The lower ends of the rods B B' are bent inward to form shallow loops or notches N N', to receive and engage the rings M M, to prevent the latter from slipping up after they have been properly adjusted.

25 The device is simple and neat, and is very easily and cheaply constructed, being preferably of wire.

It will be seen, as before stated, that the main portion of each of the sections is formed 30 of a single piece of wire, which is bent to form the different rods, eyes, and loops. It is not necessary that the said elements should be formed of a single piece of wire; but I prefer to do so, as it reduces the cost of the 35 bridle and makes it more durable; also, when on the broom the device is very inconspicuous in appearance, and its weight is inconsiderable.

In applying the bridle to a broom it is not 40 necessary to pass any of the rods or wires through the body of the same, thereby injuring the broom-corn. This bridle may be applied by any one without trouble.

The loops L L' embrace the broom-head 45 below the loops H H' and more securely hold the same in shape; but, obviously, they may be dispensed with when a shorter head is being shaped.

Having thus described my invention, I 50 claim—

1. In a broom-bridle, the combination of the side rods, B B', secured together, the ring E, to embrace the handle of the broom,

the depending rods F F', having the horizontal loops H H' at their lower ends, and 55 the links K K', connecting the lower ends of the rods F F' to the lower ends of the rods B B', substantially as specified.

2. In a broom-bridle, the combination of the side rods, B B', hinged together at their 60 upper ends, the rods F F', connected at the upper ends to the upper ends of the side rods, and having the loops H H' on their lower ends, the links K K', joining the lower ends of the rods F F' to the side rods, and 65 the sliding rings M M, embracing said side rods, B B', and adapted to draw the lower ends thereof together, substantially as specified.

3. In a broom-bridle, the combination of 70 the sections A A', adapted to embrace opposite sides of the broom, and having the side rods, B B and B' B', respectively, and the rings M M, sliding on adjacent side rods, to draw the sections together, substantially as 75 specified.

4. In a broom-bridle, the combination of the side rods, B B', hinged together at their upper ends, the arms connected to the upper ends of the said rods and provided with the 80 loops H H', the links K K', connecting the lower ends of the spring-arms to the lower ends of the side rods, and the rings M M, sliding on the side rods, the said loops H H' being adapted to compress the broom-head 85 when the lower ends of the side rods are drawn together, substantially as specified.

5. In a broom-bridle, the sections A A', formed of the continuous wires a a', respectively, and having the side rods, B B', provided at their upper ends with eyes b b', the converging arms D D', the depending rods F F', provided with eyes G G', and the loops H H', in combination with the links K K', connecting the eyes G G' to the lower ends 95 of the rods B B', and the rings M M, sliding on the rods B B', and adapted to engage in the notches or loops N N' at their lower ends, substantially as specified.

In testimony that I claim the foregoing as 100 my own I have hereto affixed my signature in presence of two witnesses.

HUGH MOORE.
